DESIGN FOR A SACHET

Jean E. Vivaudou and Henry G. Lubin,
New York, N. Y.

Application July 12, 1939, Serial No. 85,968

Term of patent 14 years

To all whom it may concern:

Be it known that we, Jean E. Vivaudou and Henry G. Lubin, subject of Great Britain and citizen of the United States, respectively, and both residents of New York city, in the county of Queens and Bronx, respectively, and both in the State of New York, have invented a new, original, and ornamental Design for a Sachet, of which the following is a specification, reference being had to the accompanying drawing, forming a part thereof.

Fig. 1 is a front elevational view of a sachet, showing our new design.

Fig. 2 is a side elevational view of the same.

Fig. 3 is a top plan view of Fig. 1.

The dominating feature of our design resides in the combination of the specific circumferential cord with the sachet ball and tassel, as shown on the drawing.

We claim:

The ornamental design for a sachet, as shown and described.

JEAN E. VIVAUDOU.
HENRY G. LUBIN.
